US0D1113168S

(12) **United States Design Patent** (10) Patent No.: **US D1,113,168 S**
(45) Date of Patent: ** Feb. 17, 2026

(54) **HAIR BRUSH**

(71) Applicant: **GIORGIO JÄNEKE S.R.L.**, Veduggio con Colzano (IT)

(72) Inventor: **Chiara Rezzonico**, Cavallasca (IT)

(73) Assignee: **GIORGIO JÄNEKE S.R.L.**, Veduggio con Colzano (IT)

(**) Term: **15 Years**

(21) Appl. No.: **35/522,523**

(22) Filed: **Sep. 13, 2024**

(80) **Hague Agreement Data**

Int. Filing Date: **Sep. 13, 2024**

Int. Reg. No.: **DM/240526**

Int. Reg. Date: **Sep. 13, 2024**

Int. Reg. Pub. Date: **Oct. 4, 2024**

(30) **Foreign Application Priority Data**

Mar. 28, 2024 (EM) 015055254-0001

(51) **LOC (15) Cl.** **04-02**

(52) **U.S. Cl.**

USPC **D4/134**
